Claims priority, application Sweden
December 20, 1949

1 Claim. (Cl. 110—7)

1

This invention relates to an improved method of burning liquid fuels and to an improved construction and operation of fuel burning apparatus especially designed for carrying out this method.

The main object of the invention is to enable effective burning of water-containing liquid fuels such as, for instance, sulphite waste lye evaporated to say 50 to 60% dry substance. Burning of such fuel directly, without any additions, in a modern boiler furnace having cooled walls will not be possible, as a rule, since the temperature in the boiler furnace will be too low. In non-cooled boiler furnaces, on the other hand, burning of such fuel may be possible under particularly favourable conditions. For example, the dimensions of the boiler furnace should be sufficiently large to give the suspended particles of the fuel injected in finely divided or atomized condition time enough to dry into an inflammable, or at least a non-sticky, condition before they meet an obstacle. In addition, for a complete combustion an air supply specially adjusted to the fuel will be necessary. Changes in an already existing boiler furnace in order to comply with these requirements may be costly and may sometimes be impossible to carry into effect.

One object of the invention is to render the burning substantially independent of the type of furnace chamber of the boiler. For this purpose the fuel is burnt in a pre-furnace in which a high temperature is maintained, and in which fuel and at least the major portion of combustion air to cause complete combustion are caused to interfere with each other in such a manner that the time of suspension of the wet fuel within a relatively small combustion chamber volume will be sufficiently long to give the fuel time enough to dry and to be intimately mixed with the air so as to cause complete combustion.

A further object of the invention is to arrange a vortex chamber or a pre-furnace of the "cyclone" type, in which a cyclone-like separating effect will take place and in which the combustion air supplied and the resulting gases of combustion are caused to whirl along the internal more or less cylindrical wall of the cyclone chamber in a cylindrical and/or conical, helical flow. In order to accomplish the desired interference the fuel is injected in or from, or in a direction

2

towards, the central portion of the cyclone and along axially or radially, or both axially and radially, directed paths relative to the cyclone chamber, the fuel particles being introduced gradually into the whirling flow so as to get completely dried, and, in most cases, also ignited, before being centrifuged against the cylindrical internal surface of the cyclone chamber. Subsequently, the fuel particles, without any risk of sticking, may be carried by the whirl in a sliding movement against the cylindrical surface through the cyclone chamber, so as to complete the combustion if not already completed during the centrifuging process. Especially, the particles which are most difficult will, in uncompletely burnt condition, reach the outermost zone of the whirl where the contents of oxygen are highest and, therefore, the conditions for combustion are most favourable. In addition, due to the friction against the wall, the velocity of the particles will be decreased in relation to the velocity of the whirl in this region, whereby an extraordinary intimate mixing with the air is obtained.

A still further object of the invention is to distribute the combustion air at a multiplicity of places along the length of the cyclone chamber and the path of movement of the whirl, so that the particles carried by the whirl will enter into a cross-current contact with the combustion air whereby the combustion process is enhanced. A specific object of the invention is to introduce the air from the peripheral region of the whirl so as to cause the air to flow from that region helically inward and thus to decelerate the particles moving radially outward to be separated. The time during which the latter particles are in suspension to be dried, ignited and burnt, will thus be increased so that a major portion of the fuel will burn in suspended condition in the central region of the whirl, whereby the ignition of freshly injected fuel is facilitated. On the whole, the method of supplying air as described above will inherently ensure that each fuel particle will contact sufficiently great amounts of combustion air even if the latter be supplied not much in excess. Therefore, it will be possible to obtain a combustion temperature approaching the theoretical maximum temperature which is of great advantage, especially when burning low-grade fuels of the kind with which the invention is concerned.

Another specific object of the invention is to effect a certain cooling of the interior wall of the cyclone chamber by means of the air thus supplied so as to prevent the temperature of the brickwork from exceeding the permissible maximum value.

A further object of the invention is to reduce the radiation of heat from the fuel particles as well as from the brickwork to cold surfaces arranged beyond the gas discharge exit. To this purpose the cyclone chamber may have a relatively large length in relation to its diameter.

A still further object of the invention is to cause the ash particles resulting from the fuel to be crushed or ground against the wall of the cyclone chamber on moving along said wall in contact with the same so as to reduce the volume of the ashes.

One embodiment of a cyclone chamber for carrying the invention into effect is shown diagrammatically in the accompanying drawing in which:

Fig. 1 shows a cross-section of the chamber taken along the line I—I of Fig. 2, and

Fig. 2 shows a longitudinal section of the same chamber taken along the line II—II of Fig. 1.

Referring to the drawing, the cyclone chamber 1 is substantially cylindrical and has at one end a restricted gas outlet 2. The chamber 1 is arranged as a pre-furnace and communicates through the gas outlet with any suitable furnace, boiler or combustion chamber, one wall of which is shown at 3. At the opposite end of the cyclone chamber there is arranged one or more substantially central supply pipes 4 for liquid fuel, each of said pipes having an atomizer or spray nozzle 5, through which the liquid is sprayed into the chamber 1 more or less axially, but the direction of the spray may also be more or less radial, or the supply may be effected along any suitable chord toward or away from the axis of the chamber 1, or a combination of any given axial and radial or chord direction may be resorted to.

The major portion of or the whole amount of the combustion air is introduced through a number of air inlets 6, extending substantially tangentially to the inner wall of the cylindrical chamber 1 and being distributed along at least the substantial part of the length of the cyclone chamber, or consisting of one elongated intake. Said inlets may be controlled individually or in common by means of throttles 7 or any suitable other means.

In operation, the water-containing liquid fuel, such as evaporated sulphite waste lye, is introduced through the nozzle 5 and intimately mixed with the air supplied through the inlets 6 so as to form a whirl passing through the chamber in a helical path. The fuel particles are introduced gradually into the whirl, the apparatus acting like a cyclone so that each fuel particle will be suspended in the whirl of gases for a sufficiently long time to get completely dried, or dried and ignited, before they will be centrifuged against the cylindrical wall of chamber 1, whereupon the particles are completely burnt in the chamber. Due to the cyclone effect the non-burnt, dried particles will be flung towards the cylindrical wall of the chamber 1 and caused to move along said wall together with the whirl. As aforesaid, such particles will be ground and their velocity reduced due to the friction against the wall, so that the air will get sufficient time to burn the particles before they leave the cham-

ber 1. Thus, when the combustion products leave the chamber 1 and enter the furnace 3 there will be no sticky particles which may deposit on the cooled surfaces of the furnace.

Burning of sulphite waste lye is also intimately bound up with the problem of handling the ashes obtained. A lye droplet which burns in suspended condition gives a thin-walled hollow ash-particle of the approximate shape of the shell of a blown egg and of the same order of magnitude as that of the droplet. Obviously ashes in this form, amounting to a quantity of about 10% of the dry-substance of the lye, will be unreasonably bulky. On account of its extremely low weight by volume the major part of the ashes will accompany the combustion gases through the furnace or boiler 3 causing a deposit on the tubes therein, and will finally be discharged through the chimney, to the detriment of the surroundings, if the ashes cannot be separated before their exit.

In accordance with this invention, on the other hand, the ash-particles will be subjected to a continuous crushing and/or grinding action against the cylindrical wall-surface of the cyclone chamber 1, so that they will lose their hollow character, whereby their weight by volume is increased so that their separation and removal by dynamical means will be facilitated. In addition, the whole quantity of the ashes will be densified, so that it will be less troublesome to remove the same and to store it as a waste product.

From this point of view it may be advantageous to make the cyclone chamber 1 of greater length than would be necessary, solely from the point of view of effecting complete combustion, in order to obtain length in excess for ensuring grinding of the ashes even from all burnt particles.

A minor portion of the combustion air may be introduced with the fuel, if desired.

Ignition of the fuel on starting the device may be effected by heating the chamber 1 internally in a suitable manner.

It should be noted that it is not necessary that the fuel is supplied in the central region of the whirl but it may also be introduced in a direction toward or from said region.

What we claim is:

A method of obtaining self-sustaining burning of a water-containing liquid fuel of highly sticky consistency in a moist state comprising in combination the steps of introducing at axially spaced intervals substantially tangentially to the circumferential inner wall of a hot combustion chamber of substantially circular cross section at least the major portion of air required for complete combustion of said fuel so as to produce and maintain in the combustion chamber a series of free spiral vortexes of said air in coaxial relation to each other in which the air moves in spiral paths towards an outlet for combustion gases from said combustion chamber, introducing said fuel under pressure in finely divided liquid state in a substantially straight line axial direction only into the central zone of those of the vortexes most remote from said outlet, the expanding fuel and air action thereby causing the wet fuel particles to be gradually brought from said central zone outwardly into the whirling motion of the air vortexes and by action of the centrifugal force to move in expanding spirals through the concentric layers of said spiral vortexes of air, while being dried to solid substantially non-sticky par-

ticles which are ignited before they reach the radial wall of the combustion chamber and at least substantially completing the combustion of the dried fuel particles while they are moving axially, with the outer layers of the vortices receiving fresh air from vortex to vortex, thereby maintaining the combustion chamber sufficiently hot to provide continuous self-sustaining burning of said fuel and removing the products of combustion from said chamber.
